UNITED STATES PATENT OFFICE.

GRANT SMITH, OF TORONTO, ONTARIO, CANADA.

WATER HEATER.

Application filed June 8, 1925. Serial No. 35,671.

The principal objects of the invention are, to obtain the maximum efficiency in the absorption of heat from a gas burner by the water to be heated, and to devise a coil structure through which the water is circulated which will concentrate the applied heat.

The principal feature of the invention consists in the novel construction of the heater coil, whereby the flame and heating gases are intercepted and directed around the heater coil containing the water by the flanges spaced from and supported by radial webs extending from the coil.

15 In the drawings, Figure 1 is a perspective view of one of my improved heater coil units.

Figure 2 is a vertical section through the line 2—2 of Figure 1.

20 Figure 3 is a small elevational view of the improved heater.

The present form of water heater consists of a tubular coil 1, preferably circular in form having a plurality of tubular radial arms 2 connected with a central hollow boss 3. This boss is provided with a centrally arranged threaded opening 4 in the upper side and the bottom of the coil where it is used at the lower end of the series or singly, 30 is provided with a conical end 5 on the underside.

A multiple boss 6 is formed on the perimeter of the coil 1 and provides a plurality of openings to the interior of the coil.

35 This may be used in any manner desired by connecting pipes to certain of the openings and blocking the others.

When the coil is to be used as a single coil in a furnace, the threaded opening 4 in the 40 boss 3 will be plugged and the feed and return pipes will be connected to the outer of the openings in the multiple boss 6 and the water will be circulated around the coil, or if the arrangement of the furnace permits, it may be desired to carry the feed pipe to one of the openings in the boss 3 and take the outflow from the centre.

Where the heater is used in a multiple arrangement, as illustrated in Figure 3, the 50 central boss is provided with threaded orifices, top and bottom. The feed pipe is connected to one of the openings in the multiple boss 6 in the bottom coil and the water circulates around the coil and up through the central boss to the next coil and spreading through the next coil, the heat applied

to the coil causes the hottest water to circulate out of the central passage and so on, the heating continues through the members of the multiple unit.

As previously stated the principal feature 60 of the coil consists in the arrangement of the flanges 7 and 8. These are thin webs of metal cast integral with the coil, being connected thereto by the radial webs 9 which hold the said flanges in position so that the 65 flames and gases of combustion from the burner flowing upward are intercepted and directed toward and around the coil 1 on both sides.

The outer flanges 7 are formed with an 70 inwardly slanting curve and they are formed in sections spaced apart in order to allow free expansion and contraction.

The inner flanges 8 are provided with a flanged upper end 10 to direct the flame into 75 close contact with the coil.

A water heater coil constructed as described, when arranged above a gas burner, will intercept the upward flow of hot gases and direct them into association with the 80 tubular conduit carrying the water so that the maximum amount of absorption of heat will occur.

The invention may be utilized for various kinds of service and being made of cast 85 metal may be produced at the minimum cost.

What I claim as my invention is:

1. A water heater comprising a coil having a series of segmental integrally cast 90 flanges extending from the bottom portions of the coil and spaced therefrom, said flanges curving inwardly from their bottom edges toward the peripheries of the coil and directing the heating gases thereagainst. 95

2. A water heater comprising a coil presenting a plurality of radially spaced peripheral surfaces, a plurality of radial webs integral with said coil and extending outwardly from said peripheral surfaces, and a plurality of radially and circumferentially spaced segmental flanges cast integral with said webs and spaced from the peripheries of said coil, the upper portions of said flanges terminating substantially intermediate of the depth of said peripheral surfaces and being curved inwardly toward the same to effect the directing of hot gases from below the coil inwardly against said peripheral surfaces. 100

3. A water heater, comprising a coil

formed with a central hollow boss having a hollow ring member spaced from and encircling said boss, a plurality of hollow radial arms connecting the hollow interiors 5 of said boss and encircling ring, a plurality of circumferentially spaced segmental flanges arranged in the space between said ring and central boss and having their side

walls curved toward the adjacent opposing walls of the boss and ring to direct hot gases 10 thereagainst, and a flange spaced from the outer wall of said ring having its wall curved inwardly to direct hot gases thereagainst.

GRANT SMITH.
